UNITED STATES PATENT OFFICE.

KARL WESSEL, OF ST. PAUL, MINNESOTA.

HEMP MACHINE.

Application filed March 5, 1923. Serial No. 622,802.

Particularly, the object of my present invention is to provide an improved hemp machine, but such machine is adapted for more general use, as will hereinafter more 5 fully appear. Generally stated, the invention consists of the novel devices and combinations of devices hereinafter described and defined in the claims.

This improved machine, in actual practice, has been found highly efficient for use in the production of both long and short fibre from hemp straw. It is adapted to act upon the straw as it comes from the field, but to obtain the best results, the hemp 15 straw should first be retted and dried. The main or first-grade product of the machine is a combing of long hemp fibre suitable for use in making rope, aeroplane canvas and the like. As a secondary product of 20 the machine, I obtain combings or short fibres suitable for making linen rugs, oakum and the like. As a third or further by-product of the machine, I obtain very short fibre, shives and woody particles suitable for 25 use in making insulating material, packing and the like.

In the accompanying drawings, which illustrate a commercial form of the improved machine, like characters indicate like parts 30 throughout the several views.

Referring to the drawings:

Fig. 1 is a plan view showing the complete machine;

Fig. 2 is a side elevation of the machine 35 shown in Fig. 1, some parts being diagrammatically indicated;

Fig. 3 is an enlarged transverse vertical section taken approximately on the line 3-3 of Fig. 2;

Fig. 4 is a fragmentary view partly in 40 side elevation and partly in section on the line 4-4 of Fig. 1;

Fig. 5 is a view chiefly in side elevation but with some parts sectioned on the line 45 5-5 of Fig. 1, showing portions of the gripper belts and cooperating devices;

Fig. 6 is a plan view of the parts shown in Fig. 5;

Fig. 7 is a view chiefly in vertical section 50 on the line 7-7 of Fig. 1, some parts being broken away and the parts being on a large scale;

Fig. 8 is a fragmentary plan showing certain parts found just below the line marked 55 8-8 on Fig. 7;

Fig. 9 is a fragmentary elevation showing

in detail certain portions of a combing device found in the vicinity of the line marked 9-9 on Fig. 7;

Fig. 10 is a view chiefly in elevation but 60 with some parts sectioned and some parts broken away, showing that portion of the machine that is in the vicinity of the line marked 10-10 on Fig. 2;

Fig. 11 is a rear elevation showing that 65 portion of the machine that is in the vicinity of the line marked 11-11 on Fig. 1;

Fig. 12 is a plan view of the parts shown in Fig. 11, some parts being broken away;

Fig. 13 is a fragmentary transverse section 70 taken approximately on the line 13-13 of Fig. 11; and

Fig. 14 is an enlarged vertical section 75 taken on the irregular line 14-14 of Fig. 12.

Directing attention first to Figs. 1, 2 and 4, the numeral 15 indicates the heavy cast framework of the breaking mechanism or machine and on which are mounted cooperative pairs of lower and upper intermeshing 80 corrugated breaking rollers 16 and 17. The lower rollers are provided with bevel gears 18 that mesh with bevel pinions 19 on a horizontal drive shaft 20 journaled in suitable bearings on the framework 15. The upper rollers 17 are capable of slight vertical movements to permit the hemp straws *y* to pass between the intermeshing corrugations of said rollers and, as shown, the bearings. 85

Said upper rollers are mounted and yieldingly pressed downward by coiled springs 21 subject to adjusting screws 22 whereby the tension of the rollers may be varied.

The cooperating pairs of rollers from the receiving toward the delivery end of the 95 breaking machine, that is, from the left toward the right in respect to Figs. 1, 2 and 4, are made progressively shallower and shallower but all have their pitch line on the same diameter. This is important because it gives the corrugated breaking rollers all substantially the same external surface, measured on the cross-section of their corrugations, and prevents breaking and stretching of the hemp fibre, but progressively reduces the woody substance of the 100 hemp straw to a finer and finer condition.

The hemp straws are laid crosswise on a feed table 23, which, at one front corner, is pivoted at 24 for angular adjustments in 110 respect to the breaking machine. Working up through the feed table 23 is a pair of

toothed feed chains 25 that run over suitably driven sprockets 26 mounted on the under side of said table. When the table is thus set obliquely to the breaking rollers, the hemp straws will be delivered obliquely between the said rollers and will be fed from the one pair of rollers to the other, not directly endwise but on oblique lines.

From the breaking rollers, the hemp straw,

- 10 straw, with the woody substance and shives quite well loosened or separated from the fibre, will be received by an elevating or endless transfer apron 27, which, as shown, is made up of two sections and arranged to run over correspondingly formed rollers 28 and 29 secured on cross shafts 30 and 31 mounted in suitable bearings on an extension 15^a of the framework 15. The shaft 31 is driven from one of the lower rollers 16 through a sprocket and chain drive 32, best shown in Fig. 1. The apron 27 delivers the fibre onto and crosswise of the receiving end of a guide rail 33 that projects between the sections of the apron 27 and extends below the upper surface thereof, as best shown in Figs. 1 and 4. This receiving end of the rail 33 is supported by the extension 15^a of the framework 15. The hemp fibre y^1 will be intermediately supported by the rail 33 and will hang down on both sides thereof. However, the rail 33 engages the fibres y^1 considerably nearer to one end than to the other, so that the fibres will hang down much further on the right-hand than on the left-hand side of said rail.
- 25 35 Here it may be stated that the rail 33 is the left-hand member of two rails, the right-hand member 34 of which extends parallel to but is offset from the first or left-hand rail 33. The rear end of the rail 33 and the front end of the rail 34 are overlapped longitudinally of the machine and rigidly supported, and the said rail 34 extends far in the rear of the rail 33. By reference to Fig. 7, it will be noted that the rails 33 and 34 are supported on a framework 36 and in cross-section are formed on their upper surfaces with laterally spaced longitudinal V shaped ridges and intervening channels.
- 40 45 50 55 60 65 70 75 80 85 90 95 100 105 110 115 120 125 130

Working directly over the rails 33 and 34

- 50 55 60 65 70 75 80 85 90 95 100 105 110 115 120 125 130
- are endless gripper belts made up of pivotally connected metallic links 37, the outer surfaces of which are formed with V-shaped grooves that quite closely fit or correspond to the upper faces of the cooperating rails. Also, these links 37 are provided with projecting gripper saw-shaped teeth 38 that work in the channels of said rails between the V-shaped ridges thereof, as best shown in Fig. 7. The gripper belts made up of the links 37 are arranged to run over sprocket wheels 39 on shafts 40 and trunnions 41. The shafts 40 and trunnions 41 are journaled in elongated supporting frames shown as made up of parallel plates 42 set edgewise in vertical planes, spaced by brackets 43, and

tied together by nut-equipped bolts 44. The brackets 43 are secured on the lower ends of hanger bolts 45, which, at their upper ends, are supported from one of the beams of a framework 46.

The lower portions of the link belts 37 are yieldingly pressed down onto the underlying cooperating rails 33 and 34 by a series of small roller-equipped levers 47, the upper ends of which are spring-connected to cooperating bars 48 anchored to the frame plates 42. These spring-pressed roller-equipped levers cause the belts and cooperating rails to hold the fibre against endwise slipping movements while it is being fed over or past the shaker and past primary and secondary or right and left hackle drums presently to be described.

The fibre delivered onto the primary or left-hand rail 33 will first be carried over or through a shaker in the form of an open rack arranged to vibrate laterally and thereby loosen and precipitate shives and woody particles and the short fibres. This shaker is preferably made of horizontal laterally spaced bars 49 cross-connected by bars 50. The bars 49 converge toward the front of the machine and are united and pivotally connected at 51, (see Fig. 4), to an adjacent portion of the frame 15. The rear portion of this shaker rack is supported by laterally movable resilient legs 52, (see particularly Fig. 3). A yoke 53 is connected to the intermediate portion of the rack and the depending portion thereof is pivotally connected to a reciprocating rod 54, the outer end of which is equipped with an eccentric strap 55 that works on an eccentric 56 carried by the rearwardly extended portion of the shaft 20. Below the shaker rack 49—50 is a so-called separating deck, the same, preferably and as shown, being a fork-like structure made up of laterally spaced tines 57 intermediately connected to a rock shaft 58 journaled in bearings 59 on the frame 46 and provided with an upstanding arm 60 to which a head block 61 is adjustably secured. This head block 61 is connected to one end of a reciprocating rod 62, the outer end of which is provided with an eccentric strap 63 that works on an eccentric 64 carried by the shaft 20. At its right-hand side and as viewed in Fig. 3, the deck 57 is arranged, to deliver onto a long endless carrier belt 65 that runs over suitably supported front and rear guide rollers 66 and 67 and is arranged to deliver to the receiving belt of a tow machine hereinafter to be described.

Shives or woody portions and other small particles that are shaken through the separating deck 57 drop onto a long endless conveyor belt 68 that runs over suitably supported and driven rollers 69 and 70.

As the fibre is moved rearward on the

5 rail 33 and as it nearly reaches the rear end thereof, the right-hand depending portion of the fibre comes into contact with a transfer cam or oblique plate 71 that is fixed to the two rails 33 and 34 and acts to carry the fibre onto the receiving end of the right-hand rail 34, and immediately after this has been done and the right-hand gripper belt has engaged the fibre, the fibre will run off 10 from the rear end of the primary or left-hand rail 33. It will now be evident that, whereas the right-hand portion of the fibre was the long end while moving on the rail 33, the left-hand portion of the fibre will be 15 the long end while moving on the second or right-hand rail 34. This is important because of the relative arrangement of the so-called primary and secondary or right and left hackle drums, which will now be described. 20

25 The right and left hackle drums are mounted to rotate on axes that extend longitudinally of the complete machine, and the right-hand hackle drum is mounted just at the right of the rear portion of the left-hand rail 33, while the left-hand hackle drum is mounted just at the left of the rear portion of the right-hand rail 34. The two hackle drums are preferably of the same 30 construction, but the two drums are arranged to be rotated in opposite directions, that is, as viewed by a person facing the receiving end of the machine, the first or right-hand drum will be rotated in an anti-clockwise direction while the second or left-hand drum will be rotated in a clockwise direction. 35

40 These so-called hackle drums, as shown and as preferably designed, comprise wheel-like heads 72 secured to shafts 73 journaled in fixed frames 74 and provided at their front ends with pulleys 75. The rims of the wheels 72 are connected by parallel circumferentially spaced angle bars 76, 77 and 78 45 that are preferably alternated in the order stated, so that the several bars make up a sort of skeleton cylinder. The bars 76 act on the fibre as scotching bars or blades for pressing the fibre while it is being combed. 50 The bars 77 hold brushes 79, preferably of wire, that remove the loosened but adhering woody portion or shives from the fibre. To the angle bars 78 are rigidly secured reversed angle bars 80, (see particularly Figs. 55 7, 8 and 9), the outer flanges of which are provided with deep notches 81. Between the flanges of the angle bars 78 and 80 are secured spring-aligning rods 82 shown as of tubular form. To provide the drum with 60 yielding hackle pins or combing teeth, I employ spring members 83, the intermediate portions of which are coiled around the aligning rod 82. The inner ends of these springs bear against the bar 78 and the

outer ends project through and are guided by the slots 81 of the angle bars 80.

65 By reference to Fig. 8, it will be noted that the pin-forming end portions 83^a of the springs 83 are sharpened so that they afford good hackle pins or comb teeth, and that they are arranged much closer together at the rear than at the front or receiving portions of the drums.

70 The above noted progressive closer spacing of the hackle pins is important because the straightening out of the fibre is produced gradually or step by step and the final combing to substantially straight condition is accomplished after the main body of fibre has first been very well straightened 80 or combed out.

75 For cooperation with each hackle drum, there is a segmental grate or concave 84, (see particularly Figs. 7 and 10). These grates are rigidly secured adjacent to the 85 drums and extend downward from the rail-supporting bars 36 adjacent to the sides of the rails from which the long ends of the fibre hang, so that said long ends of the fibre will be passed between the grates and 90 the cooperating hackle drums. At their lower portions, the grates are shown as supported by cross members 74^a of the cooperating frames 74.

95 To facilitate delivery of the long depending ends of the fibre between the drums and cooperating grates or concaves, the front ends of the hackle drums are preferably beveled or made slightly conical, as indicated at 85 in Figs. 1, 2 and 8. 100

105 To obtain the best action, the hackle drums should be quite accurately set in respect to the cooperating grates or concaves and, hence, the drum-carrying shafts 73 (see Fig. 10) are mounted in bearing boxes 86 that are obliquely adjustable and are rigidly but adjustably secured by screws 87 and 88 to bearing brackets 89 that are rigid on the frame 74.

110 Mounted below the delivery ends of the grates 84 are so-called "rattle rakes" 89 secured to rock shafts 90 journaled in the base of the frames 74 and provided with arms 91. One of the rattle rakes 89 delivers onto the rear portion of the belt 65 and the other delivers onto a similar but shorter belt 65^a, (see Figs. 1, 2 and 10). The belt 65^a runs over pulleys 92 carried by shafts 93 mounted in suitable fixed bearings and provided with a sprocket 94. Fine materials, such as the shives and extremely short fibre, will pass through the rattle rakes 84 and, by oblique plates 95, will be delivered onto the long carrier belt 68. The shives that pass through the grates 84 will fall on the deflecting plates 96 and will be directed over the belts 65 and 65^a and onto the carrier belt 68, (see particularly Fig. 10). 120

The long fibre carried off from the delivery end of the second or right-hand rail 34 may be caught on a hook-shaped arm 97 shown as secured to the under side of said rail as best shown in Fig. 2.

The hackle drums and conveyors above noted may be driven by any suitable means, but, as shown, the following driving connections are provided therefor. Mounted 10 on bearings on the tops of the two frames 74 is a longitudinal shaft 98 provided with a pulley 99 over which a power-driven belt, not shown, is adapted to run. Belts 100 run over the pulleys 75 on the drum shafts and 15 over aligned pulleys 101 on said shaft 98. The shaft 20 is driven from the shaft 98 through a belt 102 that runs over pulleys 103-104 carried respectively by said shafts. The rattle rakes 89 are vibrated by eccentric 20 trics 105 that are connected to the cooperating arms 91 by connecting rods 106, (see particularly Figs. 1 and 10). By reference to Fig. 10, it will be further noted that, of the two drum-driving belts 100, one thereof 25 is a cross belt and the other is an ordinary belt which is required to give the two drums the reverse direction of rotation already stated.

The rear shafts 40, which transmit to the 30 two gripper belts 33 and 34, may be driven by any suitable means. As shown in Figs. 1 and 2, the rear shaft 40 that drives the rear gripper belt is driven from the shaft 98, first through intermeshing bevel gears 35 107 and a sprocket and chain drive 108. Also, as shown, the rear shaft 41 that drives the front gripper belt is driven from the first noted shaft 41 through a sprocket and chain drive 109.

40 The belts 65 and 65^a may be driven by any suitable means, but, as shown, are driven from the shaft 98, first through the above noted gears 107 and then through a sprocket and chain drive 110, (see particularly Fig. 2). Moreover, as shown, the belt 45 68 is driven from the rearmost shaft 40 through a sprocket and chain drive 111, (see Fig. 2), but may be driven by any other suitable means.

50 The carrier belts 65 and 65^a both deliver to a transverse endless apron or conveyor belt 112 and this latter belt delivers the short fibre to a tow machine presently to be described. The carrier belt 68 delivers the 55 shives and fine woody particles away from the machine and is preferably driven in a direction to carry the same toward the front of the machine or from the right toward the left in respect to Figs. 1 and 2. Obviously, 60 this belt may be of any desired length and preferably will be longer than illustrated in the drawings.

The framework of the tow machine is made up chiefly of heavy latreally spaced 65 side frames 113 suitably tied together and

rigidly connected. The transverse conveyor 112 delivers to a plurality of pairs of co-operating lower and upper breaking rollers 114-115, (see Figs. 11, 12, 13 and 14). The shafts of the lower rollers are provided at 70 one end with spur gears 116 that mesh with spur gears 117 journaled on one of the side frames 113. The gears 117 are secured to rotate with larger spur gears 118, both of which mesh with a spur pinion 119 mounted 75 on a stud on the frame 113 and connected to rotate with a spur gear 120. The gear 120 meshes with a spur pinion 121 journaled on a stud on the side frame 113 and connected to rotate with a pulley 122. One of the 80 gears 118 meshes with a spur gear 123 carried by a roller 124 journaled to the side frames 113 and serving as the driving roller for the transverse belt 112.

The upper rollers 115 have shafts 125 85 journaled in bearings 126 that are guided for vertical movements by fixed posts 127 and are spring-pressed downward by coiled springs 128. The springs 128 are progressed 90 between the bearings 126 and adjusting screws 129 that are mounted in bars 130 fixed to the upper ends of the posts 127.

The rollers 114-115 are longitudinally corrugated and the pairs, from right to left in respect to Figs. 11, 12 and 14, have progressively finer and finer corrugations, the said corrugations preferably arranged on a plan more fully described in connection with the beraking rollers 16 and 17.

The last pair of rollers 114-115 delivers 100 to a toothed carding drum 131 carried by a shaft 132 journaled in the side frames 113 and provided at one end with an eccentric 133 and with fixed and loose pulleys 134-135, (see Figs. 11 and 12). Also, the 105 shaft 132 is provided with a small pulley 136 over which and the pulley 122 runs a driving belt 137. The cylindrical rim of the carding drum 131 is provided with closely positioned outwardly projecting conical teeth 110 or carding pins 138 that work close to the concave surface of a segmental grate 139 that is fixed to and supported by the side frames 113. Adjacent to the delivery pair 115 of rollers 114-115, there is a toothed segmental concave 140 that follows the line of the segmental grate 139 and has inwardly projecting teeth 141 between which the teeth of the carding drum are arranged to pass. The numeral 142 indicates a hood that closely 120 overlies the upper portion of the carding drum.

The side frames 113 have rear end extensions 113^a. A long toothed rattle rake 143 extends horizontally into the space between 125 the frame extensions 113^a and includes a rock shaft 144 mounted in the side frames and provided at one outer end with a rigidly secured bell crank 145. One arm of the bell crank 145 is equipped with a counterweight 130

146 and the other arm thereof is pivotally more than one-half of the length of the and adjustably connected, by a nut-equipped bolt 147 or the like, to the head of a connecting rod 148 that is provided at its other 70 end with an eccentric strap 149 that works on the eccentric 133 carried by the drum shaft 132.

The numeral 150 indicates a rake-like baffle, the shaft of which is arranged to be 10 hung in any one of several pairs of notches 151 formed in the upper edges of the frame extension 113^a. This baffle prevents the fibre or tow from being thrown by the drum completely over the rattle rake 143. Running 15 below the rattle rake 143, below the carding drum and grate, and below the breaking rollers 114 and 115 is an endless conveying apron 152 shown only by dotted lines in Fig. 11. This belt may be driven 20 by any suitable means and it will operate to carry the shives and fine particles caught thereby to the long conveyor belt 68.

Summary of operation.

25 The operation of the hemp machine above described has already been indicated in part, but the general operation may be briefly summarized as follows:

The hemp straw placed on the feed table 30 23 will, by the feed belts 25, be fed obliquely between the breaking rollers 17 and, by the latter, the shives and woody portions will be progressively broken and loosened from the fibre without, however, breaking or cutting 35 the fibre.

From the breaking rollers, the fibre and commingled shives and woody particles will, by the apron 27, be fed rearward and the fibre will be delivered onto the primary or 40 so-called left-hand receiving rail 33 with the ends of the long fibres hanging down farther on the right-hand than on the left-hand side. Such of the shives as are entirely free from the fibre will fall from the apron 27 45 onto the long underlying conveyor belt 68. The fibre delivered onto the said rail 33 will, by the cooperating gripper belt, be fed or slid rearward on said rail and as it is thus moved with the ends of the fibre hanging 50 through the shaker rack 49, the latter, by its vibratory motion, will loosen and shake from the fibre most of the remaining or adhering shives or woody portions and these will also fall onto the underlying conveyor belt 68.

55 As the fibre is fed between the first or right-hand carding drum 72 and its cooperating concave, the long right-hand portion, to wit: more than one-half of the fibre, will be combed out into straight condition and 60 the adhering shives or woody particles will be further removed from the fibre.

As the fibre passes further rearward, it will be transferred from the primary or left-hand rail 33 onto the secondary or right-hand rail 34, and in making this transfer,

more than one-half of the length of the fibre will be caused to hang down at the left-hand side of said rail 34 for delivery between the secondary or left-hand carding drum and its cooperating concave and 70 grate. Obviously, under the action of this secondary or left-hand carding drum, the left side and more than one-half of the fibre will be combed out into straight condition and adhering shives or woody particles will 75 be removed therefrom. Also, it will be remembered that the above noted carding actions are progressive in that they get closer and finer in the combing action toward the rear ends of said carding drums. 80

Under the carding actions above described, the spring teeth or pins 83^a perform the combing action and the edges of the bars 76 and 78 produce a scutching or scraping action which tends to remove adhering 85 shives from the fibre and the brushes 79 brush loose the fine particles, so that a very clean fibre will be delivered from the second carding drum onto the hook 97.

As already indicated, the short fibre will, 90 by the conveyor belts 65 and 65^a, be delivered to the cross belt or conveyor 68 and from thence will be delivered to the tow machine and, by the latter, will be treated and delivered in the form of tow, all as heretofore described.

What I claim is:

1. In a fibre-producing machine, the combination with breaking mechanism, of shaking mechanism receiving from said breaking mechanism, hacking mechanism receiving from said shaking mechanism, the said mechanisms cooperating to deliver long fibre at one place, short fibre at another place and shives or woody portions at still another place, and a tow-producing machine driven in cooperation with the mechanisms described and receiving the short fibre therefrom and converting the same into tow. 100

2. The mechanisms defined in claim 1 in further combination with a conveyor receiving the shives or woody portions precipitated from the several mechanisms described and including said tow machine and delivering the same at a common point of discharge. 110

3. The mechanisms defined in claim 1 in which said tow machine has a receiving conveyor arranged to operate transversely of the line of feed of the fibre through the 120 several other mechanisms described.

4. In a fibre machine, the combination with two laterally and longitudinally offset rails and means for delivering fibre onto the first thereof, of cooperating gripper belts working over the said rails, the said rails and gripper belts having interlapping ribs and channels, and means for transferring the fibre from the first to the second rail. 125

5. The structure defined in claim 4 in further combination with right and left toothed combing drums arranged to operate on the fibre moved by said gripper belts over the respective rails, and toothed combs and segmental grates cooperating with said combing drums.
6. The structure defined in claim 4 in further combination with right and left toothed combing drums arranged to operate on the fibre moved by said gripper belts over the respective rails.

In testimony whereof I affix my signature.

KARL WESSEL.
